US00D821993S

(12) **United States Design Patent** (10) Patent No.: **US D821,993 S**
(45) Date of Patent: ** Jul. 3, 2018

(54) **BUOYANT OBJECT FOR WAVE POWER GENERATOR**

(71) Applicants: **INGINE, INC.**, Seoul (KR); **Yong Jun Sung**, Guri-Si, Gyeonggi-Do (KR)

(72) Inventor: **Yong Jun Sung**, Guri-si (KR)

(**) Term: **15 Years**

(21) Appl. No.: **35/502,447**

(22) Filed: **Aug. 12, 2016**

(80) **Hague Agreement Data**

Int. Filing Date: **Aug. 12, 2016**

Int. Reg. No.: **DM/093666**

Int. Reg. Date: **Aug. 12, 2016**

Int. Reg. Pub. Date: **Feb. 17, 2017**

(30) **Foreign Application Priority Data**

Feb. 12, 2016 (KR) 30-2016-0006534

(51) **LOC (11) Cl.** **13-99**

(52) **U.S. Cl.**

USPC **D13/199**

(58) **Field of Classification Search**

(57) **CLAIM**

The ornamental design for a buoyant object for wave power generator, as shown and described.

DESCRIPTION

1. Buoyant object for wave power generator

1.1 : Perspective

1.2 : Front

1.3 : Top

1.4 : Bottom

1.5 : Cross-sectional

1.6 : Exploded
